DESIGN FOR A DISPENSING HOLDER FOR TOOTH PASTE TUBES AND THE LIKE

Walter J. Buchele, Arlington, Va.

Application October 11, 1945, Serial No. 122,739

Term of patent 14 years

(Cl. D4—3)

To all whom it may concern:

Be it known that I, Walter J. Buchele, a citizen of the United States, residing at Arlington, in the county of Arlington, and State of Virginia, have invented a new, original, and ornamental Design for a Dispensing Holder for Tooth Paste Tubes and the like, of which the following is a specification, reference being had to the accompanying drawing, forming part thereof.

In the drawing:

I claim:

The ornamental design for a dispensing holder for tooth paste tubes and the like, as shown.

WALTER J. BUCHELE.
